(57) CLAIM

(21) Appl. No.: 29/219,831

The ornamental design for a golf club face, as shown and described.

(22) Filed: Dec. 21, 2004

DESCRIPTION

(62) Division of application No. 29/186,080, filed on Jul. 8, 2003, now Pat. No. Des. 503,761.

FIG. 1 is a perspective view of a golf club face showing our new design; and,

(51) LOC (6) Cl. 21-02

FIG. 2 is a front elevational view of the golf club face shown in FIG. 1.

(52) U.S. Cl. D21/759

The broken line showing of other portions of a golf club head is for illustrative purposes only and forms no part of the claimed design.
